UNITED STATES PATENT OFFICE.

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS.

BOILER FOR FUEL-BURNING DEVICES.

Application filed July 5, 1924. Serial No. 724,297.

My invention relates to boilers and more particularly to a boiler adapted for use in connection with fuel burning devices.

The object of my invention is in the provision of a boiler of the so-called sectional type that will have increased efficiency over the present boiler structures in connection with which the well known domestic fuel burning device is used.

10 Yet another object of my invention is in the provision of a boiler adapted for use in connection with a fuel burning device wherein a forced draft is used, said boiler being fashioned in a manner to have increased to 15 a considerable extent the passage ways for the flue gases as well as providing increased contact of the gases with the flue surface by means of multiple flues and projecting stream lined lug members connected with the 20 water sections.

A still further object of my invention is in the provision of a sectional boiler adapted for use in connection with fuel burning devices and fashioned in a manner to have increased efficiency over the conventional types 25 of boiler used in connection with such burning devices.

Other objects of my invention will appear in connection with annexed specification and 30 claim.

Fig. 1 is a perspective view of the sectional boiler, portions thereof being broken away for a more detailed disclosure, there also being shown a conventional fuel burning device.

Fig. 2 is a perspective view of one-half of the boiler showing the interior arrangement.

Fig. 3 is an enlarged detail in perspective of one of the boiler sections.

40 Fig. 4 is a vertical sectional view taken on the lines 4-4 of Fig. 3.

Fig. 5 is a sectional view taken on the line 5-5 of Fig. 4, and

45 Fig. 6 is a cross-sectional view taken on the line 6-6 of Fig. 5.

Referring to the drawings I have shown in perspective in Fig. 1 my sectional boiler in connection with a conventional fuel burning device A.

50 The so-called domestic fuel burner for house installation has become so popular that progress beyond the mere perfecting of the burner itself has been made with the aim of increasing the efficiency of such devices or

rather the efficiency of the boiler or furnace 55 in which they are used.

The present practice is to install one of these domestic fuel burners in any type of furnace or boiler that the purchaser happens to own. This practice has been satisfactory 60 to a certain degree, but obviously better results or rather a greater degree of efficiency is obtained in some types of boilers than others.

The present application is directed to the 65 development of a boiler that has an increased advantage or efficiency over any of the known types of boilers in which fuel burning devices are now being installed. Obviously the 70 boilers into which these domestic oil burners are going were formerly utilizing coal as a fuel. Now the present boiler is not adapted for the use of coal for a fuel and, as a matter of fact, would only have a high efficiency when a fuel burning device with a force draft was 75 used.

Before describing in detail the present 80 boiler structure, it might be said that when coal is used as a fuel, there is usually no forced draft with the result that a high stack temperature is necessary, hence, a large draft tube, and for efficiency, a short passage way for the products of combustion in view of the necessarily stack induced air draft.

Now with the present boiler a high stack 85 temperature is not necessary, nor desired, the stack temperature usually varying between 300 and 400 degrees. The cutting down of the size of the stack is occasioned also by the use of the forced draft and also in view of this forced draft a longer and more restricted 90 passage way for the products of combustion may be made, thereby increasing the radiation surface and hence raising the efficiency of the boiler. Likewise, the multiple flues 95 that can be used, due to the construction, permit increased contact of the gases with the boiler surfaces.

I have obtained the above result in the following manner:

In Fig. 1 a perspective of the boiler is shown wherein a plurality of the boiler sections 10 are connected together by means of cement, bolts, or other conventional attachment means. These boiler sections are cast hollow in two parts or sub-sections, each part or sub-section being interchangeable and interconnecting. Each of the boiler sub-sec-

tions is the same, except the front and rear portions. As may be clearly seen, these portions merely have a flat outside face and are utilized naturally for the purpose of forming the combustion chamber 11 therein between the intermediate sections.

The front section shown in Fig. 1 is fashioned as at 12 to permit the insertion therethrough of the projecting end of the fuel 10 burning device and subsequently the filling in around such end by cement or some other substance to inclose the entire front surface of the boiler.

In the various figures of the drawing the 15 details of the sections are shown. Fig. 3, for instance, showing a perspective view of the side of a sub-section, said sub-section, of course, when placed in operative position joining with a similar shaped oppositely disposed sub-section to provide one of the main 20 boiler sections. The sub-section illustrated in Fig. 3 discloses hollow lateral extensions 10¹ about the top and side exteriors adapted to engage similar lateral extensions on the 25 next adjacent section to space apart the hollow bodies thereof to form gas flues between the vertical water legs of said sub-section and hollow water legs 19 and 19¹ adapted to meet similar water leg upon the oppositely disposed 30 sub-sections above and below the combustion chamber 11 with the upper water leg terminating in a semi-circular reentrant surface 19², the lower meeting edges of which are provided with a lateral extension 16 on 35 each side of the body similarly extending toward the exterior side and then curved toward the exterior bottom, as at 15, and extending intermediate the exterior and interior sides of the sub-section to form a baffle 14 40 adapted to engage a similar extension and baffle on the next adjacent section and form a gas flue between said exterior lateral extension 10¹ and interior lateral extensions 14, 15, and 16 to the central circular flue 20 formed 45 above the combustion chamber by the oppositely disposed reentrant surfaces 19².

Referring to Figs. 1 and 5 it may be seen that the combustion chamber 11 is provided with a lining 30 of refractory material, here 50 shown as fire bricks, laid upon the upper surface of the bottom water leg 19¹ of the sub-sections extending below the combustion chamber and carried upward at each side with the bricking engaging the opposite interior 55 of the intermediate sections terminating adjacent the under side of the central abutment of the lateral extensions 16, said lateral extensions curving downward, as at 15, out side the bricking 30 conduct the gases 60 arising from within the combustion chamber over the top of the bricking, downward between the baffle 14 and bricking and then upward between the baffle 14 and the exterior lateral extensions 10¹ to the central horizontal 65 circular flue 20, as shown by the arrows

on Fig. 3. The apertures 17 and 18 indicate the inlet and outlet respectively for the water supply. The semi-circular opening 19² in connection with similar portions upon the other sections forms a flue passage way 20 70 above the combustion chamber to which a stack 21 is connected and the abutting of the lower horizontal portions of the opposite sections forms a water leg 19¹ beneath the combustion chamber. The series of projecting 75 stream lined lugs 22 may be seen disposed in the passage way for the products of combustion. These lugs are fashioned in the stream lined manner for the purpose of keeping the products of combustion in the best possible 80 contact with the heating surface while retarding the speed thereof to a less degree than any other shape of projection that might be used.

Obviously the opposite side of the boiler 85 section shown in Fig. 3 is exactly the same as that described.

Referring now to Fig. 5, this sectional view shows the interior or water portion of the boiler section. In this view it may be seen that the stream lined lugs are formed integrally with the water section and the water 90 normally fills these lugs. Again, a baffle 23 is shown, said baffle being merely an extension of the before described baffle 14 except 95 that there is no curved or longitudinal portion. It will be remembered that the passage of the products of combustion through the gas flues was in a downward then upward manner. The circulation of the water in the 100 boiler section follows the course of the arrows shown in Fig. 5. In other words, the water near the hot side, or rather, the side adjacent the combustion chamber will rise, but after passing the upper end of the baffle will begin 105 to cool and hence take a downward movement as shown by the arrows, until the heat again affects this water, whereupon the flow will again be upward upon the inside of the baffle.

The insertion of the baffle in the water section of the boiler tends to increase the rapidity of the circulation of the water and, hence, increases the efficiency of the boiler. Another feature is the water leg 19¹ beneath 115 the combustion chamber which absorbs the heat formerly dissipated through the floor of the ash pit of the usual coal burning furnace. In addition, a water jacket extends down the whole front and back, through the front and rear boiler sections so that no opportunity is lost to utilize all of the heat generated in the combustion chamber.

Inasmuch as the forced draft of the fuel 120 burning device to force the products of combustion through the flue passage ways to the draft pipe has been described, no further 125 description of the operation of the boiler is thought necessary, except that particular attention be drawn to not only the increased 130

length and restriction of the flue passage ways and the plurality of stream lined heat absorbing lugs therein, but also to the multiplicity of flue ways.

5 The present application is directed to the boiler, but in view of the close relationship of the boiler and fuel burning device, a brief description of said device will be given.

I have shown merely a conventional fuel 10 burning device and it is clear that any type of fuel burning device utilizing a forced draft might be used. The present draft arrangement upon the fuel burning device shown is a fan member 25 contained in a 15 housing 26, the blast therefrom being projected through the tube 27 and finally into the combustion chamber of the boiler.

In view of the state of the art of domestic 20 fuel burning devices, no further description 25 of the device described is thought necessary other than to say that fuel is pumped from a tank 28 through appropriate strainer mechanism, etc., by means of an electrical power member 29, said fuel finally being discharged 30 in the form of a spray through a nozzle disposed adjacent the combustion end of the draft tube.

Naturally these fuel burning devices have 35 many systems of controls, but inasmuch as 40 the present invention has nothing to do with the fuel burning device other than to disclose the fact that a forced draft is utilized, no such disclosure of intricate control mechanism is thought necessary.

35 What I claim is:

A boiler for liquid fuel burning devices comprising a hollow front and back section with a plurality of hollow interchangeable, interconnecting, intermediate sections ar- 40 ranged therebetween and connecting thereto,

each said intermediate section formed of similarly reversable interchangeable sub-sections having hollow vertical water legs and hollow lateral extensions about the top and side exteriors adapted to engage similar lateral extensions on the next adjacent section to space apart the hollow bodies thereof to form gas flues between the vertical water legs of said sub-sections, each of said sub-sections having horizontal water legs meeting above 45 and below a combustion chamber with the upper water leg terminating in a semi-circular re-entrant surface, the lower meeting edges of which are provided with lateral extensions on each side of the body similarly 50 extending toward the exterior side and then curved toward the exterior bottom intermediate the exterior and interior sides of each section adapted to engage a simliar lateral extension on the next adjacent section and 55 form a gas flue between said exterior and interior lateral extensions to the central circular flue formed above the combustion chamber, and a refractory lining upon the upper 60 surface of said bottom water leg below the 65 combustion chamber continuing upward against the opposite interiors of the intermediate sections terminating adjacent the underside of the lateral extensions of the sections below the curved edges of the central 70 abutments, whereby the gases arising from within the combustion chamber over the top of said refractory lining pass downward between said lateral extensions and lining and thence upward between the interior and exterior side and top lateral extensions to the 75 central horizontal circular flue.

In testimony whereof, I have affixed my signature.

WALTER W. WILLIAMS.
